ICE TRAY

Jules N. Saler, Springfield, Mass., assignor to
Westinghouse Electric & Manufacturing Company,
East Pittsburgh, Pa., a corporation of
Pennsylvania

Application April 23, 1938, Serial No. 203,789

1 Claim. (Cl. 62—108.5)

My invention relates to liquid congealing apparatus, and particularly to liquid congealing apparatus for forming ice cubes suitable for domestic use.

It is an object of my invention to provide improved grid structures for congealing ice of a size suitable for domestic use.

It is another object of my invention to provide improved liquid congealing apparatus of the type from which ice is removed by mechanical force as contrasted with the use of heat; and furthermore, to so construct a grid structure that upon freeing the ice therefrom by mechanical force, the ice does not drop out of the grid structure.

It is still another object of my invention to provide improved flexible grid structures which are so constructed that ice does not fall out when the grid structure is flexed to break the ice bond between the ice frozen therein and the grid structure, when the grid structure is held in an upright position.

These and other objects are effected by my invention as will be apparent from the following description and claims taken in connection with the accompanying drawing forming a part of this application, in which:

Fig. 1 is a top plan view of an ice pan and grid structure and illustrates one preferred form of my invention;

Fig. 2 is a side view of the ice pan and grid structure shown in Fig. 1 with parts thereof broken away for clearness;

Fig. 3 is a view of the grid structure taken on line III—III of Fig. 1;

Fig. 4 is a sectional view of the grid structure taken on line IV—IV of Fig. 3; and,

Figs. 5 and 6 are detail views of a second embodiment of my improved structure.

Referring specifically to the drawing for a detailed description of my invention, numeral 11 designates an ice pan preferably formed of relatively rigid stamped aluminum and embodying end walls 12, side walls 13 and a bottom wall 14. A removable grid structure indicated generally at 15 cooperates with the ice pan 11 to provide a plurality of cells 16 forming ice cubes 17.

In the embodiment of my invention illustrated, a flexible grid structure preferably formed of a corrosion-resistant material such as stainless steel is utilized. The main features of the grid structure are disclosed and claimed in Saler Patent 2,037,519, granted April 14, 1936. As shown in Figs. 1 and 2, the grid structure 15 is formed of stainless steel sheet material bent to form a zig-

zag longitudinal wall member 18 and a plurality of transverse wall members 19 extending outwardly from opposite sides of the longitudinal wall member. The longitudinal wall member 18 is formed of two contiguous sheets of metal 21 and 22 and the transverse wall members 19 are likewise formed of two contiguous sheets of metal 23 and 24. The sheets 23 and 24 of the transverse wall members are connected at their outer ends preferably by a fold 25, thus forming an outer 10 upper corner 26 and an outer lower corner or radius 27. (See Fig. 3.) The sheets 23 and 24 are turned outwardly at the inner extremities and are fastened to the respective sheets 21 and 22 of the longitudinal wall member. The sheet 21 15 and the sheets 23 and 24 of the transverse wall members 19 which are fastened thereto are preferably formed of a single integral strip of stainless steel thus forming one half of the grid structure; and the sheet 22 and the sheets 23 and 24 20 of the transverse wall members 19 fastened to it are formed of a second integral strip of stainless steel, thus forming the other half of the grid structure.

As shown in Fig. 2, the fold 25 extends from 25 the upper corner 26 of each transverse wall member 19 to near the bottom of the edge thus formed and the sheets 23 and 24 are not otherwise connected at their outer edges, except as hereinafter described. When the sheets 23 and 24 of the 30 transverse wall members are folded at 25, and the radius is cut at the bottom corners 27, there is excess metal attached to each sheet at the radius. The excess metal is trimmed, and both the sheets 23 and 24 are bent substantially at a 45° angle to 35 the vertical in the same direction, thereby forming flaps 29 which extend partly around the radii or corners 27. The two halves of the grid shown in Fig. 1 are identical for manufacturing reasons and the flaps 29 on the respective halves, therefore, extend in opposite directions. The flaps 29 prevent the ice cubes 17 from falling out of the grid structure 15 when the ice bond between the grid structure and the ice cubes is broken by mechanical ejection.

I have provided mechanical ejecting means for removing the grid structure 15 from the ice pan 11 and for thereafter imparting relative movement to parts of the grid structure by flexing. The mechanical ejecting means comprises a pair 50 of lever members 32 pivotally fastened at 33 to each end of the grid structure 15, and having portions adapted to bear on the end walls 12 of the ice pan when the levers 32 are rotated outwardly, thus multiplying the force applied by the 55

operator for breaking the bond between the ice and the ice pan. Handle portions 35 are attached to the leverage members 32 so that the leverage means are easily operable. After the grid structure 15 with the ice frozen therein is removed from the ice pan 11, the handles 35 are grasped and relative movement is applied to the parts of grid structure 15 through the leverage members 32, by twisting or bending the flexible grid structure 15. The ice pan 11 is preferably waxed to facilitate removal of the ice therefrom.

As shown in Fig. 3, the sheets 23 and 24 of the transverse wall members 19 are preferably welded as shown at 37 at the bottom corners of the transverse wall members to impart stiffness to the grid structure as force is applied upwardly at the ends thereof, to facilitate removal of the grid structure and ice from the ice pan 11. As shown in Fig. 2, the sheets 21 and 22 of the longitudinal wall member 18 are also preferably welded together at several points, indicated by the numeral 38, to prevent undue spreading of those sheets when the grid structure 15 is flexed.

After the grid structure 15 is removed from the ice pan 11, and is flexed to release the ice cubes 17 from the grid structure, the flaps 29 prevent the ice cubes in the cells intermediate of the four corner cells from falling out of the grid structure, so that the ice cubes may be readily picked out of or from the grid structure as desired. Heretofore, in grid structures used with mechanical ejectors, the ice cubes many times would fall out of the grid structure onto the floor, or into the sink, where they naturally become dirty and contaminated so that it was necessary to wash them. Obviously, handling the cold ice cubes is undesirable, and washing wastes ice. By utilizing my invention, the ice cubes remain in the grid structure and the aforementioned disadvantages are obviated.

A second embodiment of my invention is shown in Figs. 5 and 6 and is shown applied to a flexible grid structure such as the grid structure 15 illustrated in connection with the first embodiment of my invention, and like reference numbers are, therefore, used for like parts. In the second embodiment of my invention, however, the sheets 23 and 24 of the transverse walls 19 are bent at 45° angles in opposite directions at the bottom corners 27, thus forming oppositely extending flaps 40 and 41, respectively, and extending about the radii of the bottom corners 27.

From the foregoing, it will be apparent that I have provided improved grid structures for liquid congealing apparatus of the mechanical ejection type. Although I have shown my invention applied to a flexible grid, it is obvious that it is not limited to use with that particular form.

While I have shown my invention in two forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claim.

What I claim is:

In liquid congealing apparatus, the combination of an ice pan, a removable grid structure disposed therein and cooperating therewith to provide a plurality of ice cube-forming cells, said grid structure embodying a longitudinal wall provided with corrugations to render it extensible and a plurality of spaced walls projecting transversely from opposite sides thereof and having upper and lower corners at their outer extremities, at least some of said grid walls being movable relative to each other, means for forcibly breaking the ice bond between the ice cubes and the ice pan and for imparting relative movement to said movable grid walls, and means associated with the outer lower corners of said transverse walls for supporting ice cubes when the bond between them and the grid structure is broken by said relative movement of the movable grid walls.

JULES N. SALER.
